UNITED STATES PATENT OFFICE

115,130

DESIGN FOR AN ELECTRIC RAZOR

Jean O. Reinecke, Chicago, Ill., assignor to Lion Manufacturing Corporation, Chicago, Ill., a corporation of Illinois

Application October 28, 1938, Serial No. 80,720

Term of patent 14 years

To all whom it may concern:

Be it known that I, Jean O. Reinecke, a citizen of the United States, residing at 664 N. Michigan Avenue, Chicago, in the county of Cook and State of Illinois, have invented a new, original, and ornamental Design for an Electric Razor, of which the following is a specification, reference being had to the accompanying drawing, forming part thereof.

I claim:

The ornamental design for an electric razor, as shown.

JEAN O. REINECKE.
